UNITED STATES PATENT OFFICE.

RAPHAEL S. GREEN, OF CHICAGO, ILLINOIS.

GRINDING AND STROPPING MACHINE.

1,200,421.

Specification of Letters Patent. Patented Oct. 3, 1916.

Application filed April 12, 1915. Serial No. 20,764.

To all whom it may concern:

Be it known that I, RAPHAEL S. GREEN, a citizen of the United States, residing at Chicago, in the county of Cook and State 5 of Illinois, have invented certain new and useful Improvements in Grinding and Stropping Machines, of which the following is a description, reference being had to the accompanying drawings, forming a part 10 of this specification, in which corresponding numerals of reference in the different figures indicate like parts.

My invention relates to grinding and stropping machines for sharpening razor-blades and similar cutting instruments, my 15 object being to so construct such a device that the operation may be rendered continuous while the grinding members may be driven in opposite directions from those of the honing members.

To these ends my invention consists in the combination of elements hereinafter more particularly described and definitely pointed out in the claims.

25 In the drawings, Figure 1, is a plan view of a machine embodying the features of my invention, Fig. 2, is a section taken upon the line 2—2, Fig. 1, viewed in the direction of the arrows there shown, Fig. 3, is a like 30 view taken upon the line 3—3, Fig. 1, and Fig. 4, is a central longitudinal, vertical sectional view through the sharpening rollers.

Referring to the drawings, 1, indicates the main frame of the machine in which is 35 mounted in suitable bearings, a transverse horizontal shaft 2, adapted to be driven by means of a pulley 3. A like shaft 4, is mounted in bearings in the forward ends of frame arms 5, 5, which are jointedly connected at 6, 6, to the rear ends of the frame members 1. The shaft 4 is provided with a driving pulley 7. The shafts 2, and 4, are arranged parallel to each other and are adapted to be driven in opposite directions 40 with respect to each other.

45 Arranged parallel to the shafts 2 and 4 in a plane midway between them, is a feed-screw 8, which is journaled in bearings in the frame and is provided with a driving pulley 9. Mounted in like bearings in the frame is an eccentric shaft 10, which is parallel to and in the same horizontal plane with the feed-screw 8, and is provided with a driving pulley 11. A detachable work-holder, generally designated by 12, has a 50 hinged arm 13, jointedly connected at 14 to

the main body and adapted to be clamped at the opposite end by means of a manually controlled clamp 15. The feed-shaft is passed through a screw-threaded bore 60 formed between the main body and the arm 13, while an elongated opening 16, Fig. 2, is formed between said parts for the reception of the eccentric shaft 10. Said work-holder is provided with work-holding jaws 65 17, and a clamping device 18, for holding the blades 19 to be sharpened.

The mechanism so far set forth has been described in a pending application for Letters-Patent heretofore filed by me.

70 Corresponding portions of the shafts 2 and 4 are preferably enlarged as shown at 20 and 21 respectively, Fig. 4, and have rigidly mounted thereon, rollers 22 and 23, the periphery of each of which is covered 75 with leather 24, or other suitable stropping material.

76 Loosely mounted upon the reduced portions of said shafts are metal hubs 25, 26, said hubs having pulleys 27 and 28, respectively, Figs. 1 and 4, upon their outer ends. Secured by means of keys 29, 30 Figs. 3 and 4, upon the hubs 25 and 26, are one or more, but preferably a plurality of rings 31, 32, 33 of stone, emery or other suitable abrading material, which are separated by means of leather or other washers 34. Washers 35, are also inserted between the abrading rings 33 and the stropping material 24.

80 The operation of the device is as follows: 90 The pulleys 27 and 28 are independently driven at like speeds and in opposite directions as indicated by the arrows shown in Figs. 1 and 3, so as to move the grinding surfaces toward the edge of the blade 19, 95 to be ground, which blade is vibrated between the two rollers by the movement of the work-holder 12, actuated in turn, by the rotation of the eccentric shaft 10, and pivoted upon the feed-screw 8. At the same 100 time the shafts 2 and 4, which are driven in opposite directions with respect to each other, are also reversed with respect to the direction of movement of the grinding rollers, and caused to move away from the edge 105 of the blade 19, as indicated by the arrows shown in Fig. 2.

85 The operation is intended to be continuous. The work-holder 12 is placed in position upon the right-hand ends of the eccentric shaft and feed-screw, and is fed toward 110 the left, so that the work will first be

brought into contact with the grinding ring or rings and thence passed to the stropping surface. When the work-holder is fed to the left-hand end of the honing rollers, it 5 is removed,—the lengths of said rollers being such as to completely finish the sharpening process.

It will be apparent that a number of work-holders may be employed at once, one 10 being attached upon the right as another is removed from the left.

The great advantage of the improvement lies in the fact that a blade may be ground and stropped in a single operation while the 15 grinding and stropping surfaces are moved in opposite directions with respect to each other,—thereby preventing the formation of a wire-edge in the grinding process and greatly facilitating the work.

20 I do not wish to be limited to the precise construction shown inasmuch as it may be varied without departing from the spirit of the invention. For example, it is immaterial which element is made loose upon the shaft, provided the direction of movement is reversed and they are so driven that the grinding surface may be caused to move toward, and the stropping surface away from, the edge of the article to be sharpened.

Having thus described my invention, I claim:

1. A grinding and stropping machine, comprising in combination, parallel shafts, 35 each having mounted thereon grinding and stropping rollers one of which is loose and the other rigid upon the shaft, means for rotating said shafts in opposite directions, means for rotating said loose members in 40 opposite directions with respect to said shafts, means for supporting work in a plane between said rollers, means for causing a lateral movement between said rollers and work with respect to each other to bring the work into successive contact with 45 said grinding and stropping surfaces and means for alternately causing contact between said work and the rollers upon said opposite shafts.

50 2. A grinding and stropping machine,

comprising, in combination, parallel shafts, each having mounted thereon grinding and stropping rollers one of which rollers is loose and the other rigid upon the shaft, means for rotating said shafts in opposite directions, 55 means for rotating said loose members in opposite directions with respect to said shafts a work-holder mounted in a plane between said rollers, means for moving the same laterally to bring the work 60 into successive contact with said grinding and stropping surfaces and means for alternately causing contact between said work and the rollers upon opposite shafts.

3. A grinding and stropping machine, 65 comprising, in combination, parallel shafts each having mounted thereon grinding and stropping rollers, one of which rollers is loose and the other rigid upon the shaft, means for rotating said shafts in opposite directions, 70 means for rotating said loose members in opposite directions with respect to said shafts, a work-holder mounted in a plane between said rollers, means for moving the same laterally to bring the work into 75 successive contact with said grinding and stropping surfaces, and means for vibrating said holder to alternately bring said work into contact with the opposing rollers.

4. A machine of the class described, comprising, in combination, parallel shafts arranged to be rotated in opposite directions, cylindrical grinding and stropping members mounted upon each of said shafts, one being loose thereon and the other rigid therewith, 85 means for rotating said loosely mounted members in opposite directions with respect to each other and to said shafts, means for alternately bringing work into operative contact with opposing members, and means for moving the same laterally to successively bring it into contact with said grinding and stropping surfaces.

In testimony whereof, I have signed this specification in the presence of two subscribing witnesses, this 9th day of April, 1915.

RAPHAEL S. GREEN.
